(57) **CLAIM**

The ornamental design for an upper shell for a shoe, as shown and described.

DESCRIPTION

FIG. 1 is a top perspective view of an upper shell for a shoe, showing our new design;

FIG. 2 is a front view of the upper shell shown in FIG. 1;

FIG. 3 is a rear view of the upper shell shown in FIG. 1;

FIG. 4 is an outer side view of the upper shell shown in FIG. 1;

FIG. 5 is an inner side view of the upper shell shown in FIG. 1;

FIG. 6 is a top view of the upper shell shown in FIG. 1; and,

FIG. 7 is a bottom view of the upper shell shown in FIG. 1. In the drawings, the broken lines in FIGS. 1-5 and 7 depict portions of the design that form no part of the claim.

1 Claim, 5 Drawing Sheets
